UNITED STATES PATENT OFFICE

ROYAL DOUGLASS, OF SOUTH BELLINGHAM, WASHINGTON

CAN PACKER

Application filed December 15, 1928. Serial No. 326,266.

This invention relates to means for packing sealed and labeled cans in boxes and its primary object is to reduce labor and cost and expedite the work. The invention provides 5 mechanism whereby the cans may pass by gravity into a rotatable hopper until the number required to fill a case have been received, the hopper then rotated to set the cans on end, and the cans then lifted from 10 the hopper and carried to and deposited in a case. The invention is illustrated in the accompanying drawings and consists in certain novel features which will be hereinafter first fully described and then particularly 15 defined in the appended claims.

In the drawings, Figure 1 is a side view of a machine embodying the invention;

Figure 2 is a rear end elevation;

Figure 3 is a longitudinal vertical section;

20 Figure 4 is a horizontal section in the plane of the axis of the rotatable hopper;

Figures 5 and 6 are transverse sections;

Figure 7 is a detail elevation of a portion 25 of the suction mechanism;

Figure 8 is a view partly in plan and partly in horizontal section;

Figure 9 is a detail horizontal section showing part of the rocking hopper structure;

30 Figure 10 is an enlarged detail section of a part of the rocking hopper;

Figures 11 to 18 inclusive are details of the 35 rocking hopper parts;

Figure 19 is a section of the line 19—19 of Fig. 6;

Figures 20 and 21 are details of cams on the rear hopper;

Figures 22 and 23 are details;

40 Figures 24 to 29 inclusive show details of the can stops;

Figure 30 is a detail of a suspension hook;

Figures 31 and 32 are detail plans of the parts of the suction head;

Figure 33 is a section through the suction 45 head;

Figure 34 shows the upper track rails in detail.

The machine embodying the present invention is preferably portable in order that 50 it may be shifted from place to place as the

exigencies of operation may require, for which purpose there is provided a truck comprising a bed plate 1 and a supporting frame 2 mounting the bed plate at its front end upon a fifth-wheel 3 and at its rear end upon an 55 axle 4, the latter fitted with wheels 5 and the former carrying wheels 6 and having a draft pole 7 attached thereto whereby the truck may be hauled and steered. It may be observed that the frame 2 is of such form that 60 the front end of the bed plate is at a higher elevation than the rear end thereof. At intervals along one side edge of the bed plate are secured brackets 8 which are disposed transversely of the bed plate and each of 65 which has a foot member 9 riveted or otherwise rigidly secured to the under side of the plate, a vertical member or leg 10 rising past the edge of the base plate, a top member or bridge 11 extending inwardly from the upper end of the leg 10, and an inner leg 12 depending from the bridge to rest on the bed plate. Supported by these brackets and secured rigidly upon the bridging portions 70 thereof are longitudinal angle bar rails 13 which constitute a track and guide for the case as the latter passes to the position in which it receives the cans. Secured to the under side of the rails are bearing boxes 15 75 in which are mounted rolls 16 extending between the rails and of such diameter that the high points of their circumferences will occupy a plane above the horizontal webs of the rails to support a case out of actual contact with the rails and facilitate its travel 80 to the working position. It will be understood that the rolls are provided in such number and in such relation that there will always be at least two rolls under a case to support it against rocking, and that the cases are successively placed on the front end of the track 85 and gravitate to the rear end thereof.

To arrest the travel of the case when it reaches the can receiving position, I provide a bolt or stop pin 17 slidably housed in a tubular guide 18 secured rigidly upon the bed plate 1 at the rear edge thereof, the bolt being of such length that it may project from the upper end of the guide into the path of the case, as will be understood. The lower 100

end of the stop pin is pivoted to a crank arm 19 projecting rearwardly from a rock shaft 20 which is journaled in bearings provided therefor on the underside of the bed plate 1 and is normally held in such position that the stop pin is projected by a torsion spring 21 coiled around the shaft and having one end secured to the shaft and its opposite end secured to an adjacent bearing. To the outer end of the rock shaft is attached a foot lever 22 which passes downwardly and rearwardly at the outer side of the rear wheel. When a case has been filled, pressure upon the foot lever will withdraw the stop pin, whereupon the filled case will pass by gravity from the track. When the case is over the stop pin, it will hold the pin depressed and the lever may be released so that the instant the case clears the pin the latter will be projected upwardly by the spring 21 to stop the travel of a succeeding case.

Secured to the base plate and rising therefrom along the edge remote from the brackets 8 and also immediately adjacent the inner 25 track rail 13 are standards 23, the inner track rail being rigidly secured to the adjacent intermediate and rear standards. Between the foremost standards a hopper 24 is disposed, and this hopper is rigidly supported 30 by brackets 25 disposed between and secured to the bed plate 1 and the bottom of the hopper.

It will be noted at once that the bottom of the hopper, in its forward portions is inclined sharply downwardly and rearwardly so that cans placed therein on their sides will at once roll to the rear open end of the hopper. Within the hopper are vertically spaced shelves or tracks 26 constituting runs 35 for the cans, the entrances 200 being so arranged that the cans will pass onto the lowest run until it is filled and will then pass onto the next higher run and so successively fill all the runs. Extending from the hopper 40 are a series of vertically spaced tracks or runs 27 which incline downwardly and rearwardly and through which the cans roll to the rear rotatable hopper. These runs each comprise a bottom or track plate 28 and 45 side rails 29 rigidly secured on said plates along the edges of the same, the inner faces of the rails being slightly dished, as indicated at 30, to reduce frictional contact with the ends of the cans. The corners of 50 the plates are notched to abut the rear sides of supporting bars 32 and pass through notches in the flanges 34 of said bars to be supported. The forward bars 32 are secured rigidly to the sides of the hopper 24 while 55 the rear bars are erected upon the bed plate 1 immediately in advance of the rear hopper.

To control the travel of the cans, stops are provided at the rear end of the front hopper and at the rear ends of the runs. A rock shaft 60 65 35 is journaled in suitable bearings on

the brackets 25 beneath the front hopper, this shaft being provided at its center with a crank 36 which depends therefrom and normally projects slightly rearwardly. To this crank is pivoted the front end of a connecting bar 37 which rests slidably on the bed plate 1 and is held thereon by headed fasteners inserted through longitudinal slots 38 in the bar, the movement of the bar being thereby limited and held to a rectilinear path.

To the rear end of the bar is secured a cross bar 39 to which is secured a rearwardly projecting yoke 40, and on the upper side of this yoke, at its center, is mounted a roller 41 against which a cam 76 on the rear hopper 75 may impinge to drive the same and the connected parts rearward, a contractile spring 42 attached to the bar 37 and to the bed plate holding the parts normally drawn forward.

To the ends of the shaft 35 are secured cranks 43 which extend rearwardly and slightly upwardly at the sides of the bracket 25 and have their rear ends pivoted to the lower ends of the extractor bars 44 which are mounted to slide in vertical guides on the sides of the hopper 24. These guides consist each of a main bar 45 having a T-shaped cross section with a flange 46 projecting from the stem 47 of the T parallel with the head thereof, and an angle bar 48 secured to said flange 47 so as to form, with the same and the T-head, a box enclosing the extractor bar and open at top and bottom. In that side of the bar 48 which is presented to the bar 45 and the extractor bar are horizontal grooves 49 which correspond in number and location to the can runs, and in the opposed surface of the extractor bar are correspondingly located inclined grooves 50. Stop pins 51 are slidably mounted in the grooves 49 and on the pins are lugs 52 slidably fitting in the grooves 50, the result of the arrangement being that the vertical reciprocation of the extractor bars causes horizontal movement of the stop pins to project them into the paths of the cans or retract them therefrom. The cans are fed into the front hopper 24 from the labeling machine and are arrested by the stop pins until all the runs are filled whereupon the release of the cans and their subsequent stoppage is controlled by the rear hopper which automatically operates the stops.

The rear stops, indicated as an entirety by the numeral 53, are essentially the same as the front stops just described but the extractor bars are connected at their upper ends by a cross bar 54 at the center of which is a roller 55 arranged to be engaged by a cam projection 540 on the rear hopper.

The rear hopper comprises front and rear heads and a can receptacle extending between and carried by said heads. The rear head 56 is a circular disk or plate having, in its front face, a groove 57 parallel with and at one side of a diameter of the plate, and

- branch grooves 58 leading from said groove 57 at right angles thereto. The front head 5 comprises a front circular plate or ring 59 having a circular recess 60 in its rear side, and a rear circular plate or disk 61 having a circular projection 62 on its front side to fit closely but rotatably within the recess 60, and at the center of each plate is an oblong opening 63 which forms an inlet for the cans.
- 5 10 Attaching brackets or feet 64 are secured to the disk 59 and to the bed plate 1 whereby the front end of the hopper is supported, the inlet opening 63 in said disk having its longer diameter extending vertically. To the rear head 56 is secured a trunnion or stub shaft 65 which is journaled in and extends through a bearing bracket 66 secured upon the bed plate 1 at or near the rear end thereof, and at the rear of said bracket a sprocket 67 is secured upon the trunnion while at the extremity of the same is secured a handle or operating lever 68. The disk 61 has grooves 69 around three sides of the opening 63 which correspond to the groove 57 and the end 20 25 30 35 40 45 50 55 60 65 grooves 58 in the disk or head 56, and a plate 70 is fitted at its edges in the respective grooves 57 and 69 while plates 71 are engaged in the grooves 58 and alined notches provided therefor in the front head.
- 30 The plates 71 are provided with lugs 72 to engage in notches 73 in the end edges of the plate 70, and angle brackets may be secured to the plate 70 and the side plates 71 to impart rigidity to the structure, tie rods 75 being threaded in and extending between the disks 56 and 61 for a like purpose and to maintain the relation between the disks to support the plates 70 and 71. The opening 63 in the front disk 59 is alined with the runways 27 so that cans on the runways may pass through said opening unless the rear stops above described are projected, and when the cans are to pass the rear opening 63 is also vertically disposed, at which time the plates 71 form, in effect, continuations of the runways 27. If the filled hopper be given a quarter turn, the cans will be held in rows by the plates 71 and will be supported on end by the plate 70. A cam block 76 is secured to the disk 61 and projects therefrom to engage the roller 41 and operate the front stop pins as indicated in Fig. 9. When the hopper is swung from receiving to delivering position, the cam block 76 impinges upon the roller 41 to actuate the connected mechanism for retracting the front stops, the rear stops being simultaneously projected. When the hopper returns to receiving position, the cam block, 540 will impinge upon the roller 55 to actuate the connected mechanism for retracting the front stops, the rear stops being simultaneously projected. To limit the movement of the hopper to a quarter turn, stop lugs 77 are secured to the rear head 56 in position to impinge against the bearing bracket 66 and arrest the rocking of the hopper at the proper instant.
- Over the rear hopper, transverse track bars 78 are secured to the opposed sides of the rear and intermediate standards 23 to carry rails 79, and the front bar 78 has bearing posts or brackets 80, 81, erected thereon at its ends, and at one end of the rear bar 78 is secured a bracket 82 corresponding to the bracket 81. A shaft 83 is journaled in the bearings 81, 82, and has a sprocket 84 at its rear end, a chain 85 being trained about said sprocket and the sprocket 67. Near the front end of the shaft 83 a sprocket 86 is secured thereon, and a similar sprocket 87 is secured upon a stub shaft journaled in the bracket 80, a chain 88 being trained about the sprockets 86 and 87 as shown. A draw-bar bracket or post 89 (see Fig. 2) is rigidly secured upon a carriage plate 90 and is also secured to the chain 88 whereby the travel of the chain will be effective to shift the carriage in unison with the rocking of the rear hopper. To the under side of the carriage plate, adjacent the corners thereof, are secured legs 91 carrying rollers 92 which run on the tracks 79 and support the carriage, the corners of the carriage plate being recessed, as at 93, to accommodate the rollers.
- Secured upon the upper side of the carriage plate in rectangular relation are cup flanges 94 into which are threaded the lower ends of guide tubes 95 through which are slidably fitted guide rods 96 which extend through the carriage plate and have their lower ends secured to the transfer plate 97, the upper ends of the rods being connected by braces 98.
- The transfer plate or suction head comprises a lower rectangular member 99 having openings 100 therethrough and an upper member 101 having a plurality of intersecting grooves 102 in its under side, the points of intersection, when the parts are assembled, being axially alined with the respective openings 100, and carried on the underside of the transfer plate are suction cups 103, each in direct communication with one of the openings 100. The described construction and arrangement provides a vacuum chamber leading to each suction cup, and it is to be understood that the suction cups correspond in number and arrangement to the cans which are to be cased, usually four rows of six cans each. At any preferred point on the top of the transfer plate, in communication with a groove 102 is a nipple 104 which is connected through a hose 105 with a controlling valve 106, said valve being also connected through a hose 107 with a vacuum tank 108 carried on the underside of the bed plate 1 of the truck. Carried by standards 23 and projecting forward above the stationary hopper are beams 109 carrying a suction pump 110 and its motor 115 120 125 130

- 111, the pump being connected through a hose 112 with the vacuum tank.
- Secured upon the carriage plate 90 and positioned centrally over the transfer plate 97 is a cylinder 113 within which is a tight-fitting piston 114, a connecting rod 115 being attached to the piston and depending therefrom through a central opening 116 in the carriage plate 90. The lower end of the rod 115 is firmly connected to the transfer plate, preferably by being threaded into a socket 117 secured on the plate, it being seen that the transfer plate is carried by the connecting rod. The upper end of the cylinder is closed by a head 118 having a central opening 119 in which is fitted an elbow 120, a hose 121 leading from the elbow to a valve 122 of the same construction as the valve 106 and also connected to the hose 107.
- The suction cups 103 each comprise a tubular body 123 having an internally threaded opening at each end. A tubular plug or nipple 124 is threaded at its upper end into one of the openings 100 of the transfer plate 25 and depends therefrom through a ring nut or collar 125 whereby the cup body 123 is suspended from the transfer plate, the plug having an annular sustaining flange 126 at its lower end to engage under the lower end 30 of the nut and support the same in an obvious manner. A tubular screw 127 is fitted in the lower end of the cup body 123 and has a spreading conical head 128 at its lower end to support the flexible washer 129 and secure 35 the central portion of the same in the widely flaring seat or recess 130 in the lower end of the body, the entire edge of the washer or cap being free to rest on and conform to the can top and enable a high vacuum to be formed.
- To maintain the transfer plate in raised position so that the carriage may be moved back and forth when the vacuum is broken, a suspension hook 131 is provided. This hook has a long shank which is passed upwardly through an opening in the carriage plate and through a boss 132 thereon, the boss having a diametrical notch 133 in its upper edge to be engaged by a lug 134 on the lower end of a nut or handle 135 which is secured 45 on the upper end of the shank. Normally, the beak of the hook is turned out of the path of the transfer plate and it will be held in that position by the engagement of the flat-sided lug 134 in the flat-sided notch 133.
- When the hook is to be operative, the handle 135 is grasped and lifted to clear the notch 133, the hook, of course, following the movement. The handle and the hook are then given half a turn so that the beak of the hook will be engaged under the transfer plate 60 whereupon the lug and notch are reengaged.
- Below the plane of horizontal travel of the suction cups, a plurality of rollers 136, arranged in rectangular relation, are supported on the side of the main frame to guide the cans as they are delivered into the case.
- In the operation of the machine, the cans are fed into the front hopper until there are at least six cans in each row, the rear hopper having both inlet openings extending vertically at this time. The lever 68 is then rocked to turn the rear hopper ninety degrees which automatically opens the front stops and permits the cans to roll down the can runs to the rear stops which are now closed. The rear hopper is then rocked back to its initial position causing the front stops to close and the rear stops to open, whereupon cans will roll into the hopper and rest upon the plates 71. The hopper is then again rocked, as at first, and the cans will be caused to rest on end upon the plate 70, the carriage being now directly over the hopper. The valve 122 is now set to slowly break the vacuum in the upper end of the cylinder 113, permitting the piston to descend so that the suction cups will be carried down onto the cans. The valves 106 and 122 are then both set in position to establish vacuum creating suction which will lift the piston and the cans. The hopper is then again rocked into vertical position to receive another load of cans, the carriage being simultaneously moved to a position over the case 14, whereupon the valves are manipulated to lower the cans into the case, release the cans and then raise the transfer plate. The transfer plate is then returned to the position over the hopper, the hopper being simultaneously rocked to set the cans on end and the cycle of operations is repeated as long as there are cans ready to be cased.
- Having fully described my invention what I claim as new and desire to secure by Letters-Patent, is:
1. The combination of a pivotally mounted hopper, means whereby cans may roll into the hopper in a plurality of rows arranged one row above another, means for rocking the hopper to set the cans on end, and means for removing all the cans simultaneously from the hopper and delivering them into a case.
  2. The combination of a hopper, means whereby cans may roll into the hopper in a plurality of vertically arranged rows, means for turning the hopper to set the cans on end, means for supporting a case at one side of the hopper, and means for simultaneously transferring all the cans from the hopper to the case while maintaining the relative positions of the rows of cans and the cans in the rows.
  3. The combination of a hopper, means whereby cans may roll into the hopper, means for turning the hopper to set the cans on end, and means remote from the hopper and actuated by the turning of the hopper to control the travel of cans thereto.
  4. The combination of a hopper, runways leading into the hopper, means for turning the hopper to set on end cans received from

the runways, and means in the sides of the runways at points remote from the hopper controlled by the turning of the hopper to regulate the travel of cans on the runways.

5. The combination of a hopper, runways leading into the hopper, means for turning the hopper to set on end cans received from the runways, stops arranged at the sides of the runways, and means actuated by the turning of the hopper to project and retract the stops.

6. The combination of a stationary hopper, a pivoted hopper, runways between the hoppers to deliver cans from the stationary hoppers to the pivoted hopper, stops arranged at the ends of the runways to control the travel of cans thereover, means for turning the pivoted hopper to set cans therein on end, and means controlled by the turning of the hopper to set the stops in alternation.

7. The combination of a hopper, means whereby cans may roll into the hopper, means for turning the hopper to set the cans therein on end, a transfer plate, means on the transfer plate to pick up the cans, and means for moving the transfer plate in unison with the turning of the hopper to carry the cans to a point of delivery beyond the hopper.

8. The combination of a pivoted hopper, means whereby cans may roll into the hopper, means for turning the hopper to set the cans on end, a carriage above the hopper, means for effecting travel of the carriage to and fro in unison with the turning of the hopper, and means on the carriage to lift cans from the hopper and deliver them at a point removed from the hopper.

9. The combination of a pivoted hopper, means whereby cans may roll into the hopper, means for turning the hopper to set the cans on end, a carriage above the hopper, means for effecting travel of the carriage to and fro in unison with the turning of the hopper, means on the carriage to lift cans from the hopper and deliver them at a point removed from the hopper, and means for guiding the downward delivery movement of said means.

10. The combination of a pivoted hopper, means whereby cans may roll into the hopper, means for turning the hopper to set the cans on end, a carriage above the hopper, a transfer plate below the carriage, means on the carriage to raise and lower the transfer plate, and suction cups on the transfer plate to engage the cans.

11. The combination of a pivoted hopper, means whereby cans may roll into the hopper, means to turn the hopper to set the cans on end, a carriage above the hopper, a suction cylinder on the carriage, a piston in said cylinder, a transfer plate carried by said piston, and means on said plate to engage the cans.

12. The combination of a pivoted hopper, means whereby cans may roll into the hopper,

means to turn the hopper to set the cans on end, a carriage above the hopper, a suction cylinder on the carriage, a piston in said cylinder, a transfer plate carried by said piston, and suction cups on said plate to engage the cans.

13. The combination of a pivoted hopper, means whereby cans may roll into the hopper, means to turn the hopper to set the cans on end, a carriage above the hopper, a suction cylinder on the carriage, a piston in said cylinder, a transfer plate carried by said piston, suction cups on said plate to engage the cans, and valves on the carriage controlling the suction in the cylinder and the cups.

14. The combination of a pivoted hopper, means whereby cans may roll into the hopper, means for turning the hopper to set the cans on end, a suction plate including an upper member having intersecting channels in its lower side and a lower member having openings therethrough communicating with said channels, suction cups secured in the openings in the lower member to engage cans in the hopper, a nipple on the top of the plate in communication with the channels and a source of suction, means for raising and lowering the plate, and means for effecting travel of the plate to and fro.

15. A hopper for the purpose described comprising front and rear heads, the front head having an oblong inlet opening therethrough, a plate extending between the heads and supported thereby in substantial alignment with one side of the inlet opening, and other plates abutting the first plate and arranged parallel with the ends of the inlet opening.

16. The combination of a fixed support, a hopper mounted therein to rock about a horizontal axis and annularly spaced stops on one head of the hopper to impinge against opposite sides of the support and limit the turning movement of the hopper in either direction.

17. The combination of a hopper, a carriage mounted to travel to and fro above the hopper, a transfer plate suspended from the carriage, means to raise and lower the plate, and a hook mounted on the carriage and engageable under the transfer plate to hold it raised.

18. The combination of a rotatable hopper, runways down which cans may roll into the hopper, stop pins slidably mounted in the sides of the runways, and means operated by the hopper as the latter turns whereby the stop pins will be projected into or retracted from the runways.

19. The combination of a rotatable hopper, runways down which cans may roll into the hopper, posts at the sides of the runways, stop pins slidably mounted in the posts and having lateral studs, vertically movable bars having obliquely disposed grooves in their sides engaging the studs, and means operated by the hopper as the latter turns to vertically

reciprocate the bars and thereby project the pins into or retract them from the runways.

20. The combination of a rotatable hopper, runways down which the cans may roll into the hopper, stop pins mounted at the sides of the runways to extend thereinto, vertically reciprocable bars mounted on the sides of the hopper and operatively connected with the stop pins to project or retract the same, a 5 rock shaft mounted below the runways, cranks at the ends of said shaft connected to the lower ends of the bars, a slide having its front end operatively connected with said rock shaft and its rear end disposed adjacent the hopper, yieldable means for holding the 10 slide in its rear position, and a projection on the hopper to engage the rear end of the slide and move the same forward.

In testimony whereof, I have signed this
20 specification.
